United States Patent Office

Des. 183,375
Patented Aug. 12, 1958

183,375

DRIVE-IN SALES BUILDING

Richard G. Schorling, Denver, Colo., assignor to Continental Air Lines, Inc., Denver, Colo., a corporation of Nevada

Application June 7, 1956, Serial No. 41,808

Term of patent 14 years

(Cl. D13—1)

FIG. 1

FIG. 2

Des. 183,375

PAGE 2

FIG. 3

FIG. 4

FIG. 5

Fig. 1 is a top plan view of a drive-in sales building embodying my new design;

Fig. 2 is a front elevation view of the building shown in Fig. 1;

Fig. 3 is a rear elevation view of the building;

Fig. 4 is a side elevation view of the building; and

Fig. 5 is an enlarged sectional view of the building taken near the base thereof.

The other side of the building is the same as that shown in Fig. 4, in reverse.

I claim:

The ornamental design for a drive-in sales building, as shown and described.
